UNITED STATES PATENT OFFICE

HERBERT H. BUNKER, OF JERSEY CITY, NEW JERSEY

FLOOR UNIT

Application filed May 24, 1929. Serial No. 365,620.

This invention relates to metallic flooring and, more particularly, to a solid floor unit having a surface of metal and of concrete or other filling material.

5 Among the objects of the invention is to provide a floor panel or unit having a surface of metal and of concrete or other filling material which may be manufactured in the shop and laid down in units.

10 Another object of the invention is to provide an armored floor surface of metal and of filling material which has a walking surface of filling material separated by metallic structure and in which the filling material 15 is in a unitary form though interspersed with metallic structure.

Other objects and advantages of the invention will be pointed out hereinafter in the description and in the claims.

20 Some of the former types of armored flooring used have characteristics which are undesirable and at least limit the usefulness of the flooring. For example, some former types are only suited for such conditions as 25 permit the manufacture of the armored flooring as it is being laid in the ultimate position it is to occupy. Other forms of armored flooring have many individual units of filling material in the fashion of tesselated work supported by the bars of reticulated structures.

30 Both of these forms of armored flooring have apparent limitations and the second form of armored flooring is undesirable for certain uses because of the fact that the filling material or concrete which fills the open spaces of the reticulated structure takes the form of individual concrete units unconnected from one another. While having in mind the problem of designing a practical armored 40 floor unit which is characterized by the objects primarily stated, I further propose that my armored floor unit be devoid of the disadvantages inherent in the types of floor units above referred to.

45 In the drawing I have illustrated my preferred form of floor unit and I wish it to be understood that the manner by which the various metallic structures are formed and associated with one another may be varied 50 to suit the style and whim of a designer

either for the purpose of producing a desired pattern of the reticulated metallic structure appearing in the floor or for the purpose of utilizing different forms of bent bars and of channels other than those I have illustrated by way of example. 55

In the drawing:

Fig. 1 is a plan view of a portion of an armored floor unit partly filled with concrete.

Fig. 2 is a section of the unit of Fig. 1 on line 2—2 showing the relation of concrete to the metallic structure. 60

Fig. 3 is a section on line 3—3 of Fig. 1.

It is convenient to refer to the metallic structure or skeleton of an armored floor unit by designating the bottom portion thereof as a base portion and the upper-most portion thereof as a reticulated structure. The base portion is formed by a plurality of members 10 arranged parallel to one another and having webs 11 in one plane and upwardly extending flanges 12. These members may be made of flat strips with bent edges or they may be built-up from two or more pieces of material or constitute standard members such as structural channels or ship building channels. Depending upon the width and size of floor unit desired, the members or channel bars 10 will be selected according to size and in such numbers as to form a structure sufficiently strong and of a desired size for any particular installation. 70 75 80

In the embodiment of the invention illustrated the channel bars 10 are secured together by rivets 13 engaging through their up-standing flanges 12. It is convenient to support the reticulated structure above the base portion by means of straps 15 which may be held in place by the rivets 13 which secure the channel bars 10 to one another. 85 The upwardly extending straps 15 are placed between the outer surfaces of the upwardly extending flanges 12. Since these straps are of a relatively narrow width there will be a long open space between adjacent flanges 12 of adjacent channel bars 10 which extends from one strap to another, but this space is of such a narrow proportion that its presence does not operate detrimentally against the efficacy of the structure. 90 95 100

The reticulated structure which is to be united to the base portion to form a complete metallic skeleton is made up of oppositely arranged bent bars 16, 17 which have dimensions permitting the accommodation of two associated bent bars 16, 17 within the width defined by two laterally positioned straps 15. As in the case of the fastening means for the channel bars, rivets 18 may be employed for fastening together bent bars 16, 17, and similar fastening means 19 may be employed for fastening two bent bars, 16, 17 to the upper end of each of the straps 15. While I have used rivets for this purpose it is appreciated that any other manner of fastening can be utilized and that the associated members may be secured together by means of a welding operation or by bolts. In order that the open areas formed by the bent bars bordering the reticulated structure may be closed at their outer edges I provide strips of metal 20, 21 along each longitudinal edge of the grating unit. However these are not indispensable since if the skeleton is to be used to contain a filling material, temporary detachable side strips can be used for retaining the filling material within such areas until it has had a chance to set. This procedure may be followed in closing the open areas appearing in the grating unit at its ends, but, as in the case of the longitudinal edges, permanent vertical strips may be used at the ends of the unit.

While I have just described a preferred form of my metallic skeleton I wish it to be understood that one of the features of my invention is to provide a structure which may be used with or without a suitable body of filling material and which when used with a suitable body of filling material it confines the filling material as one unitary slab. The unitary slab is interspersed with metallic elements and by virtue of the relation of the reticulated structure to the base portion the divided areas created by interspersed metallic elements are in connection with one another through a substantial amount of filling material. This is well illustrated in Fig. 2. The first two channel bar sections from the left are shown as filled-in with solid filling material and the third and fourth sections illustrate how communication is had between adjacent bent bars 16, 17 and above the upwardly extending flanges 12 of adjacent channel bars 10. This form of floor unit permits all of the pressure directed upon the upper surface of a concrete area between bent bars to be transmitted to a footing of larger area of filling material whose lower surface is in contact with a plurality of channel bars forming the bottom of the base portion of the metallic skeleton.

Since the metallic skeleton may be used as a floor grating without any filling material therewith or may be sold for the purpose of manufacturing into an armored concrete

floor unit in the manner described hereinbefore or may be sold as an armored floor unit with filling material, it is appreciated that either with or without filling material associated with the metallic skeleton, a useful article of manufacture is had.

I claim:

1. A flooring unit comprising a base portion built-up of channel members having their flanges secured to each other and their webs forming the bottom wall of the flooring unit, longitudinal strips of metal secured to and bordering the full lengths of the outside flanges of the exterior channel members, said strips of metal extending above the height of the flanges, a metallic floor surface structure comprising reticulated bars, said floor surface structure being disposed above the flanges of said channel members, strips of metal connecting the flanges and surface structure at intervals spaced throughout the surface area of the flooring unit, said floor surface structure being within the area of said longitudinal metallic strips, and filling material imbedding the flanges of the channel members and the floor surface structure.

2. A flooring unit comprising a base portion having a plurality of channel bars arranged alongside of each other with their flanges extending upwardly, said channel bars being permanently secured together by means connecting adjacent flanges, a reticulated structure disposed above said base portion and having open areas immediately above the flanges of said channel bars, means connecting said reticulated structure and said base portion, said means comprising metallic strips extending above the exterior flanges of the channel members and strips of metal fastened to the flanges and reticulated structure, and filling material contained between the flanges of said channel bars and the open areas of said reticulated structure.

In testimony whereof I hereto affix my signature.

HERBERT H. BUNKER.
